PNEUMATIC VACUUM CLEANER

Thomas H. Huff, Philadelphia, Pa.

Application December 10, 1935, Serial No. 53,788

5 Claims. (Cl. 15—14)

This invention relates to a vacuum cleaner the blower of which is actuated by a fluid, such as steam or air, under considerable pressure. The object of the invention is to provide such vacuum cleaner having a dust receiving mouth piece which can conveniently and easily be handled by being disposed at the end of a pliable, light, and compact vacuum hose, and having also a shut-off for the actuating fluid in direct, convenient, and immediate reach of the operator. Another object is to provide for such vacuum cleaner in which all actuating fluid is well disposed of and carried away in such fashion as to obviate any annoyance of operator. Still another object is to provide for such vacuum cleaner in which no actuating fluid is wasted. Other objects and advantages of the present invention will appear from the following specification.

I obtain all these advantages by branching the supply line for the actuating fluid. Two supply lines for the actuating fluid are provided, a wide one and a narrow one, each with its own shut-off valve. The actuating fluid supplied by either line is utilized and suitably disposed. The valve of the narrow line is placed near the operator and in easy reach of his hand. This does not bring about excessive bulkiness and weight of the mouth piece carrying member, because the narrow line and its valve are comparatively light and compact. The wide line and its valve are necessarily heavy and bulky. They are therefore disposed away from the operator, far enough to relieve him from the immediate presence of their bulk and weight. The heavy valve is nevertheless under the control of the operator, namely immediately. This heavy valve is pressure responsive, and so operatively communicates with the narrow supply line as to respond to its pressure. The two valves therefore open and close almost simultaneously, the bigger valve following the smaller valve.

The fluid supplied by either line is neither permitted to be wasted, nor to annoy the operator. The fluid supplied by the major line actuates the blower. The fluid supplied by the narrow line is utilized for augmenting or complementing the dust collecting function of the cleaner. All actuating air is disposed together with the dust bearing air.

These and other desirable objects and advantages of the present invention will be illustrated in the accompanying drawing and described in the specification, certain preferred embodiments being disclosed by way of illustration only, for, since the underlying principles may be

incorporated in other specific devices, it is not intended to be limited to the ones here shown, except as such limitations are clearly imposed by the appended claims.

In the drawing like numerals refer to similar parts throughout the several views, of which Fig. 1 represents a section through a pneumatic vacuum cleaner embodying my invention,

Fig. 2 represents the same section through the manually operated valve of that cleaner in a larger scale,

Fig. 3 represents in similar section a variation of the portion of the cleaner represented in Fig. 2, in that the dust is stirred up and agitated by a jet of compressed air, and

Fig. 4 represents in a larger scale a section parallel to that of Fig. 1 through the automatic valve of the vacuum cleaner.

The cleaner Fig. 1 consists of a casing 10 with perforations 11 and containing a dust bag 12, a major jet pump composed of the venturi 13 and a jet nozzle 14, a pliable and flexible vacuum hose 15, a mouth piece 16, a minor jet pump 17, a major supply line 18, a minor supply line 19, a manually operated single valve 20 in the minor supply line 19, a pressure responsive single valve 21 in the major supply line 18, the minor line communicating with the pressure responsive valve by virtue of opening 22. These parts are mutually arranged as shown in Fig. 1, hose 15 being however shown somewhat shorter than it would mostly be made, in order to accommodate the drawing on the sheet. The dust bearing air enters into the mouth piece 16, flows through the vacuum hose 15, by the minor jet pump 17, then through the jet pump venturi 13 by the jet nozzle 14, enters the dust bag 12 and leaves the cleaner through the perforations 11, after having deposited the dust in the bag. Compressed air enters the pump at the primary pressure supply 23. Most of it flows directly through the major supply line 18, including major valve 21, through the nozzle 14 and mixes then with the dust bearing air. A minor portion of the compressed air enters the minor supply line 19 at the opening 22, passes the manually operated valve 20 and enters at last through the opening 26 into the vacuum hose 15. The opening 26 is disposed adjacent the shoulder 27 of mouth piece 16. The jet entering at 26 is therefore turned into a down stream direction and imparts energy and momentum to the stream of the dust bearing air while mixing therewith.

The automatic valve 21 consists of cylinder 30, of piston 31 within the cylinder in sliding but

not necessarily tight fit therewith, of valve seat 32 at the bottom of the cylinder, of valve cone 33 at the bottom of the piston, and of a helical spring 34 in chamber 35 held between cylinder 5 cover and piston. A bypass 25 connects chambers 35 and 36 on both sides of the piston 31, there being an adjustable throttle 24 in that bypass. Any looseness between piston 31 and cylinder 30 serves likewise as such bypass, and in 10 case the adjustable feature 24 is dispensed with, the bypass 25 may be dispensed with and its function entirely be performed by the piston clearance. The valve cone 33 is adapted to open and to close supply line 18 by engaging and dis- 15 engaging seat 32. Opening 22 establishes the operative communication between the automatic valve 21 and the minor supply line 19 recited in the claims at the end of this specification.

When the cleaner is out of use, valve 20 is 20 closed. Spring 34 keeps the piston 31 at the left of Fig. 4, the fluid pressure in front and in rear of the piston being then equal, and the needle valve 32 and 33 is thereby kept closed. For starting the operation, valve 20 is opened. 25 The pressure in line 19 and consequently the pressure in chamber 35 is then diminished. The pressure in chamber 36 in front of the piston is hardly at all diminished. Hence spring 34 is compressed, the piston is moved to the right, and 30 the needle valve is opened. When valve 20 is closed again, the pressure in spaces 35 and 36 becomes again equalized, and the piston closes again needle valve 32 and 33 under the action of spring 34 together with aerodynamic pressure 35 effects.

Fig. 3 shows a variation of the cleaner shown in Fig. 1 and Fig. 2. In this case, the air supplied by the minor line 19 and flowing through the valve 20 enters the vacuum hose through the 40 mouth piece opening together with the dust bearing air and mixes therewith, after having been released adjacent of the opening at 38 for the purpose of stirring up and agitating the dust.

I claim:

45 1. A pneumatic vacuum cleaner comprising a suction mouth for the reception of dust bearing air, a flexible vacuum hose for receiving said air therefrom, a jet pump drawing said air from said hose, a line for supplying actuating fluid to said 50 jet pump, a branch from said line, a valve in said line responding to the pressure in said branch, a manually operated valve in said branch positioned adjacent the entrance end of said hose for operating said first valve, and an auxiliary jet 35 pump aiding in moving said dust bearing air supplied with actuating fluid by said branch.

said branch, and a manually operated valve in said branch positioned adjacent the entrance end of said hose for operating said first valve.

2. A pneumatic vacuum cleaner comprising a suction mouth for the reception of dust bearing 5 air, a flexible vacuum hose for receiving said air therefrom, a jet pump drawing said air from said hose, a line for supplying actuating fluid to said jet pump, a branch from said line leading into said hose, a valve in said line responding to the 10 pressure in said branch, and a manually operated valve in said branch positioned adjacent the entrance end of said hose for operating said first valve.

3. A pneumatic vacuum cleaner comprising a 15 suction mouth for the reception of dust bearing air, a flexible vacuum hose for receiving said air therefrom, a jet pump drawing said air from said hose, a line for supplying actuating fluid to said jet pump, a branch from said line leading along 20 at least a portion of said hose, a valve in said line responding to the pressure in said branch, and a manually operated valve in said branch positioned adjacent the entrance end of said hose 25 for operating said first valve.

4. A pneumatic vacuum cleaner comprising a suction mouth for the reception of dust bearing air, a flexible vacuum hose for receiving said air therefrom, a jet pump drawing said air from said hose, a line for supplying actuating fluid to said 30 jet pump, a branch from said line, a valve in said line responding to the pressure in said branch, a manually operated valve in said branch positioned adjacent the entrance end of said hose for operating said first valve, and an auxiliary jet 35 pump aiding in moving said dust bearing air supplied with actuating fluid by said branch.

5. A pneumatic vacuum cleaner comprising a suction mouth for the reception of dust bearing air, a flexible vacuum hose for receiving said air 40 therefrom, a jet pump drawing said air from said hose, a line for supplying actuating fluid to said jet pump, a branch from said line, a valve in said line responding to the pressure in said branch, a manually operated valve in said branch positioned adjacent the entrance end of said hose 45 for operating said first valve, and a dust agitating jet nozzle supplied with actuating fluid by said branch.
